(57) **CLAIM**

The ornamental design for an eyeglass case, as shown and described.

DESCRIPTION

FIG. 1 is a perspective view of an eyeglass case showing my new design;

FIG. 2 is a front elevational view thereof, the rear being a mirror image;

FIG. 3 is a top plan view thereof;

FIG. 4 is a right side elevational view thereof;

FIG. 5 is a left side elevational view thereof;

FIG. 6 is a bottom plan view thereof; and,

FIG. 7 is an inside elevational view; the case being shown in an open position.

The items shown in dotted lines are for illustrative purposes only and do not form part of the claimed design.

The broken lines shown on the inner and outer edges, and on the inner holder features in FIGS. 1, 2, 6, and 7, are understood to represent stitching.
